DOOR KNOB

George P. Patriquin, Gardner, Mass., assignor to Independent Lock Co., Fitchburg, Mass., a corporation of Massachusetts

Application December 12, 1957, Serial No. 48,873

Term of patent 14 years

(Cl. D50—3)

The dominant features of the design reside in the portions shown in full lines.

I claim:

The ornamental design for a door knob, substantially as shown and described.
